TIE PLATE

Gilbert H. Werner, Portage Township,
Porter County, Ind.

Application February 26, 1932, Serial No. 595,389

4 Claims. (Cl. 238—304)

My invention relates to improvements in tie plates and it more especially consists of the features pointed out in the claims.

The purpose of my invention is to produce tie plates from single flat plates by die press stamping; that provides raised projections on the upper surface of the plate by pressing corresponding recesses on the under side of the plate so as to maintain the structural integrity of the plate; that forms a cant on the upper surface over a central area of the plate; that combines a camber with the cant so as to produce a curved face for the rail to rest on; that in one form provides supporting projections for rail holding washers; that in another form produces rail positioning ledges pressed up from the body of the plate; and that in the latter embodiment a combined cant and camber is formed between the rail positioning ledges. The exemplification shown in Figs. 1-6 20 includes the special rail fastening means embodied in application Serial Number 558,296.

With these and other ends in view I illustrate in the accompanying drawings such instances of adaptation as will disclose the broad underlying features of the invention without limiting myself to the specific details shown thereon and described herein.

Figure 1 is a top plan view of a special form of tie plate.

- 30 Fig. 2 is an elevation in section of Fig. 1.
Fig. 3 is a front elevation of Fig. 1.
Fig. 4 is a detached elevation of a portion of Fig. 1 in section on line 4—4 of that figure.
Fig. 5 is an elevation in section on line 5—5 of Fig. 1.
Fig. 6 is an end elevation of Fig. 1.
Fig. 7 is a top plan view of an ordinary form of tie plate.
Fig. 8 is an elevation in section on line 8—8 of Fig. 7.
Fig. 9 is a front elevation of Fig. 7.
Fig. 10 is an elevation in section on line 10—10 of Fig. 7.
Fig. 11 is an elevation in section on line 11—11 of Fig. 7.
Fig. 12 is an end elevation of Fig. 7.

In producing and installing my improved tie plates I may use whatever alternatives or equivalents of structure that the exigencies of varying conditions may demand without departing from the broad underlying features of the invention.

It has been proposed heretofore to form tie plates with a canted upper surface running from end to end of the plate crosswise of the rail length by rolling methods and also form the camber

crosswise of the plate from one edge to the other by the same method. I have made a radical departure from this practice by pressing up the central portion of the plate to form the sloping and cylindrical curved upper face of the plate by pressing the material up from the underside and avoiding the defect of running the cant and camber to the edges of the plate. Such a rolling operation is quite expensive because special rolls must be made for each change in size and style of tie plate. Furthermore, it is well known that it is not practical to secure a uniformly shaped plate by rolling the camber in it.

It has also been attempted to press a camber in a punch press with the curve of the camber forming a true arch from one edge of the plate to the other. Without a reinforcing between the margins of the camber and the edges of the plate it does not possess the required rigidity. This causes it to soon flatten out under the recurring pounding of heavy traffic. In my method only the center of the plate is canted or cambered as desired or both configurations may be made on a single plate. In this way the opposite edges of the plate are made parallel with each other thus producing a die plate that at all times will lie flat on the tie and the raised center portion will not become flattened under the heaviest loads of railway traffic. Plates embodying my invention may be manufactured at less cost than other forms in use at the present time. In addition they can be made more uniform in every way. The same advantages of pressing up the cant or camber from the body of the plate over a central portion only enables me to produce the ordinary type of tie plate which is held in place by means of driven spikes.

The exemplification illustrated in Figures 1-6 inclusive comprises a flat plate 1 provided with holes 12 for securing it to the tie by means of screw spikes or otherwise. The center portion of the plate has a lengthwise cant 2 formed with its lowest point at 3 and its highest point at 4. Likewise the same area may have a curved contour or camber 5 crosswise of the plate and lengthwise of the rail (not shown). The cant 2 or camber 5 is formed so as not to reach the side edges of the plate. This leaves a flat margin along side of the raised center. In this type of plate special rail fastenings are shown, that is, the projections on which fastening washers (not shown) are attached. These projections include raised bosses 6 adjacent the center area and raised supports 9 in which recesses 10 are formed.

Between the supports 9 and the bosses 6 an

opening 8 is made through the thickness of the plate. This opening leads to a recess 11 on the under side of each one of the bosses 6. It is connected to the slot 7. The openings 8, recesses 11 and slots 7 are for the use of fastening bolts (not shown). Recesses 11 permit the heads of the bolts to be seated therein and the openings 8 permit the insertion of the fastening bolts from above without loosening the plate from the tie. It will be noted in Fig. 5 that the camber 5 pressed up from beneath substantially leaves the raised portion of the plate of the same thickness with a hollow 19 on the underside. This is an important point in my method. The cross section of the plate is preserved so that its strength is not reduced. In the formation of the bosses 6 and washer supports 9 the extent that the material is raised above the upper surface of the plate corresponds to recesses beneath. The metal removed from the openings 8 and slots 7 is used to build up the projections 9.

In Figures 7 to 12 inclusive a modified tie plate 13 is exemplified. It simulates the ordinary form of plate which is fastened by well known spikes or otherwise through openings 16. The center area is formed the same as in Figures 1 to 6 inclusive. On each side of the canted-cambered area up-standing flanges 14 and 15 are formed. The base of the rail (not shown) is positioned between these flanges. There are two at one side and one at the other side, respectively at 15 and 14. Beneath the flanges or abutments 15 recesses 17 are formed and beneath the shallower abutments 14 recesses 18 are formed by pressing the metal upward. The difference in height of the flanges 14 and 15 conforms approximately to the slope of the canted surface 2. This relation is also followed in Figs. 2 and 3 in which the left hand projection 9 is shallower than the one on the right.

The camber 5 may approximate a slightly conical surface or a cylindrical curvature of approximately ten foot radius.

It will be apparent from the description and the drawings that I have devised a method of forming canted or cambered tie plates in a new and novel manner, in such a way as to retain the structural rigidity of a flat plate by maintaining the cross section of the plate uniform throughout the flat and the raised portions. In addition to these fea-

tures it is obvious that my tie plates can be made of less weight than is usual, thus effecting a large saving in their use.

What I claim is:

1. A tie plate comprising a relatively thin and flat unitary plate, a raised area on the upper surface inclined in one direction and curved in a direction approximately at right angles to the incline adapted to receive the weight of passing traffic, a corresponding recess on the under side of the plate, and a reinforcing margin of the unitary plate enclosing the raised area, said plate being provided with rail positioning and fastening means within the reinforcing margin. 80

2. The tie plate comprising a relatively thin and flat uniform plate, a raised area on the upper surface canted lengthwise of the plate and cambered crosswise of the plate, a recess of approximately similar shape on the underside of the plate, a reinforcing margin retaining the original thickness 85 of the plate which margin entirely encloses the canted and cambered configuration, and rail positioning projections formed on the upper surface of the plate adjacent the configuration, said projections having a recess beneath the same of 90 approximately the same contour. 95

3. As an article of manufacture, a flat plate of approximately uniform cross section with a portion enclosed by a reinforcing margin, said plate having a canted and cambered raised portion on 100 which a railway rail is to be seated the surface not included in the canted and cambered area being raised at isolated points to position the rail and having recesses on the underside of the plate of approximately the same contour as the configuration 105 on the top of the plate. 110

4. As an article of manufacture, a tie plate for the support of a railroad rail, said plate having an approximately uniform thickness throughout, the upper and underside surfaces being an approximate duplicate of each other, the upper surface having a raised canted shape in one direction and a raised cambered shape at approximate right angles to the canted surface, without encroaching on a margin of the original plate that extends all 115 around the outer edge of the plate and projections formed on the upper face adapted to position a railroad rail on the formed surfaces. 120
